(57) **CLAIM**

The ornamental design for a vinyl record player, as shown and described.

DESCRIPTION

FIG. 1 is a top, front and right side perspective view of a vinyl record player showing my new design;

FIG. 2 is a bottom, rear and left side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of an encircled portion of the vinyl record player labeled "9" in FIG. 1; and,

FIG. 10 is an enlarged view of an encircled portion of the vinyl record player labeled "10" in FIG. 1.

The broken lines show features of the vinyl record player that form no part of the claimed design. The broken lines in FIGS. 1 and 9-10 encircling portions of the vinyl record player illustrated in enlargements form no part of the claimed design.

1 Claim, 10 Drawing Sheets
